UNITED STATES PATENT OFFICE.

THOMAS P. STRAUP, OF SOUTH EASTON, PENNSYLVANIA.

WIRE-DRAWING DEVICE.

SPECIFICATION forming part of Letters Patent No. 354,991, dated December 28, 1886.

Application filed March 22, 1886. Serial No. 196,093. (No model.)

To all whom it may concern:

Be it known that I, THOMAS P. STRAUP, a citizen of the United States, residing at South Easton, in the county of Northampton, State 5 of Pennsylvania, have invented certain new and useful Improvements in Wire-Drawing Devices, of which the following is a specification, reference being had therein to the accompanying drawings.

10 My invention is a die, through which wire is drawn for reducing the same.

It consists in the construction of parts, which will be hereinafter described, and pointed out in the claims.

15 In the accompanying drawing, Figure 1 is a perspective view of a portion of the die-holder provided with two of my dies. Fig. 2 is a central longitudinal vertical section taken through the die-holder and dies. Fig. 3 is a 20 top plan view of one of the dies.

Like letters indicate like parts in the several views.

25 The letter A indicates the die-holder, preferably constructed of iron. This die-holder is provided with a series of openings tapering from a large opening in the top B to a smaller opening on the lower side, (marked B'). Said die holder is also provided with a small recess, C, on its upper side communicating with 30 the opening B.

35 D represents my improved die with a funnel-shaped opening therein. (Indicated by the letter D'.) The sides of the die taper from the top downward, so as to fit snugly in the die-opening, said opening constituting a seat for the die. The top and bottom parts of the die are parallel, and are in a line with the top and bottom, respectively, of the die-holder.

40 E represents a lug on the upper side of the die. This lug is adapted to fit into the recess C in the die-holder, whereby the die is prevented from turning in the die-holder while wire is being drawn. The lug E is also for the purpose of preventing the turning of the die 45 in the die-holder A when the die is being reamed.

The operation of the device is as follows: The wire is passed into the top of the funnel-shaped opening and then drawn through the 50 small bottom opening, d, until it is reduced to the desired size in the usual manner.

The old means for drawing wire consisted in

an iron block with ten to sixteen holes in it. The iron rod, being heated, was drawn through repeatedly until reduced to the proper size. 55 These holes in the beginning are of the same size, but become rapidly enlarged, and are then used for larger size of wire until they become too large. A good die with ten holes will stand the use of one man about a day. The 60 openings are then rereamed to nest a larger size. After being rereamed five to eight times it becomes worthless, except for old iron, and, as it must be of best quality, the waste is very great.

65 My dies last about the same time as the old form and go through the same process as the old die; but the die-holder or case can be used for an unlimited time. Thus the loss when dies are sold for old iron is trifling.

70 Having thus described my invention, what I claim as new, and desire to secure by Letters Patent of the United States, is—

75 1. A die for wire-drawing having a central opening and sides tapering from top to bottom, the upper outer part of said die being provided with a laterally-projecting lug, so as to be held without turning in a suitably-recessed die-holder, substantially as specified.

80 2. A die for wire-drawing detachable from the die-holder, and having a central opening with tapering sides tapering from top to bottom, the upper outer part of said die being provided with a laterally-projecting lug, in combination with a die-holder provided with 85 an opening adapted to receive the die, said opening being provided with a lateral recess near its top adapted to receive the die lug, substantially as specified.

85 3. The combination of the die-holder A, 90 having conical openings, each provided with the recess C, with the detachable dies D fitting into said openings, and each provided with the funnel-shaped opening D' d, and the lug E to enter the recess C and prevent the die from 95 turning when being reamed, substantially as specified.

In testimony whereof I affix my signature in presence of two witnesses.

THOMAS P. STRAUP.
